(57) **CLAIM**

The ornamental design for a cutting tool for adhesive tape dispensers, as shown and described.

DESCRIPTION

1, 3 Cutting tool for adhesive tape dispensers

1.1 : Front

1.2 : Back

1.3 : Right

1.4 : Left

1.5 : Top

1.6 : Bottom

3.1 : Front

3.2 : Back

3.3 : Right

3.4 : Left

3.5 : Top

3.6 : Bottom

The reproductions depict cutting points on the top or bottom edges of the cutting tools; the tools are made of rigid materials, enabling them to act as manual cutters when using adhesive tape; at the end of the process, the tools may remain as tabs on the end of the tape for future use and assistance in locating the end of the tape.
